Attorney

UNITED STATES PATENT OFFICE.

HUGH C. BURRUS AND GEORGE A. TORRENCE, OF HOT SPRINGS, VIRGINIA.

THERAPEUTIC GLOBE.

Application filed February 20, 1926. Serial No. 89,704.

This invention relates to improvements in therapeutic apparatus, and particularly to an evacuated lamp therefor.

It has been found that in the various types of therapeutic apparatus in present use, which in most cases use reflected rays from a source of light, that the full benefit of the treatment cannot be obtained with these reflected rays as readily as where direct rays are used.

It is an object of the present invention to provide a lamp construction for therapeutic apparatus in which the direct rays from the source of light may be obtained in their full force and with the rays extending in parallel relation from the filament.

A further object of the invention is to provide for the use of direct rays in therapeutic treatments by providing a bulb construction in which the evacuated container for the filament has an enlarged filament chamber provided with a flat end portion and mounting the filament in a plane spaced and parallel with relation to this slotted portion in order to prevent the distortion of the rays of light by the glass of the receptacle in the projection therethrough by refraction.

The invention comprehends numerous other objects residing in the special construction and arrangement of the evacuated container and filaments which are more particularly pointed out in the following detailed description and in the claims directed to a preferred form of the invention, it being understood, however, that various changes in the arrangement and construction of these parts may be made without departing from the spirit and scope of the invention as herein set forth.

40 In the drawing forming part of this application:

Figure 1 illustrates a side elevation of the lamp construction and the shield applied thereto, portions being shown in vertical longitudinal section:

Fig. 2 is a bottom elevational view of a structure as shown in Fig. 1.

Fig. 3 is an enlarged detail transverse section thru the lower end of the evacuated container and filament showing the relation of these parts.

The improved globe of this invention includes an evacuated container 1 which is provided with a base 2 adapted for attachment with a standard electric screw socket, and which is formed at the opposite end with an

enlarged filament chamber 3. This bulb or globe 1 is adapted to receive the lead shield 4 usually used with lamps of this character in therapeutic apparatus.

The end portion transversely of the axis of the evacuated container 1 indicated at 5 is formed of glass having a uniform thickness, and having the surface thereof entirely flat and lying within a single plane.

The filament 6 is formed of a length of strip material having the flat face 7 disposed toward the flat end portion 5 of the evacuated container and which is formed in zig-zag relation as illustrated in Fig. 2 with the entire length of the filament lying within a single plane in spaced parallel relation with respect to the flat ends 5 as clearly illustrated in Figs. 1 and 3. The opposite ends of the filaments extend as indicated at 8 through the base of the evacuated container, and are electrically connected with the terminals of the lamp or globe so as to be properly interposed in an electric circuit connected with a socket in which the lamp may be placed.

Suitable additional supporting wires 9 are used to support the filament intermediate the ends as clearly illustrated in order that it may be maintained in a plane parallel with the flat ends 5 of the container.

In operation, it will be seen that the flat face 7 of the filament strip is disposed directly toward the flat end 5 of the container so that a large number of parallel rays of light are projected from the filament within the single plane in spaced parallel relation thru the flat or plane ends 5 of the container, without distortion by refraction or in any other manner, so that the rays leaving the globe or bulb may be directed in a straight path for obtaining the direct action of the rays in the treatment of the body for stimulating blood supply, the inhibition of the growth of bacteria, etc., and hastening the healing of the pathological parts and producing asepsis.

This special construction of therapeutic lamp or globe for producing these results in the treatment of the body are more efficient and will penetrate deeper through the direct parallel rays, given off from the flat surface of the filament that can be obtained with any other form of container or filament construction which may be used.

Having thus described our invention, what we claim as new is:—

1. A therapeutic globe, comprising an evacuated receptacle having an enlarged filament chamber formed with a flat end portion of uniform thickness, and a filament mounted in said chamber and extending within a single plane in spaced parallel relation to said flat end portion and having a flat surface disposed in parallel relation with said flat end. 15
2. A therapeutic globe, comprising an evacuated receptacle having an enlarged filament chamber formed with a flat end, and a filament formed of a flat strip of material mounted in a plane within the chamber in spaced parallel relation to said flat end. 20
3. A therapeutic globe, comprising an

In testimony whereof we affix our signatures.

HUGH C. BURRUS.
GEORGE A. TORRENCE.
